UNITED STATES PATENT OFFICE.

WASHINGTON I. BROWN, OF SAVANNAH, MISSOURI.

ASEPTIC CLINICAL-THERMOMETER HOLDER.

1,017,377.

Specification of Letters Patent. Patented Feb. 13, 1912.

Application filed December 23, 1910. Serial No. 598,903.

To all whom it may concern:

Be it known that I, WASHINGTON I. BROWN, a citizen of the United States, residing at Savannah, in the county of Andrew 5 and State of Missouri, have invented certain new and useful Improvements in Aseptic Clinical-Thermometer Holders, of which the following is a specification.

The object sought by me in this invention 10 is to provide an aseptic holder for a thermometer especially adapted to the use of the medical profession and in the use of which the constant danger of a thermometer conveying bacteria from the mouth or throat 15 of one patient to that of another will be absolutely eliminated.

I accomplish my object by the mechanism illustrated in the accompanying drawings, in which,

20 Figure 1 is a longitudinal section of the device showing its entire interior construction, and Fig. 2 is an elevation thereof, the outer barrel shown partly broken away, an inner perforated barrel with the thermometer 25 therein also shown partly broken away.

Similar letters refer to similar parts in the two views, in which—

A is an outer case or barrel, its bottom A' threaded for the purpose of engagement 30 with a cap B having a projection b threaded on its outer end. The upper end of said case or barrel has an inner flange C having an upward projection C' of the same thickness as the flange, said projection having a 35 threaded outer surface d to engage with the inner threaded portion of an upper cap D. Cap B is adapted to be filled to a line horizontal with the base of projection b with solidified formaldehyde gas E. An inner 40 perforated tubiform barrel F, of copper or other suitable material, is inserted into said outer barrel, its bottom resting solidly on the solidified formaldehyde gas E in cap B, while it is held snugly in position by said 45 projection b at the bottom and by flange C at its top. The chamber formed by the outside of this inner tubiform barrel, the wall of the outer barrel, projection b and flange C is also filled with the solidified formalde-

hyde gas E. The entire body and bottom 50 of said inner barrel is provided with perforations f f. A bifurcated spring metal clasp H is seated rigidly in the top of cap D; it is adapted to receive and clasp the handle M of a clinical thermometer I. 55 When cap D is unscrewed to use the thermometer the thermometer may remain seated in its clasp the cap serving as a holder therefor, or it may be withdrawn from its clasp. When the thermometer is re-inserted 60 in said inner barrel after use in the mouth of a patient any bacteria or germs that may have gathered thereon are speedily annihilated by the formaldehyde gas that escapes from the solidified packing through said 65 perforations f f into the inner barrel chamber in which the thermometer is suspended.

It should be understood that if, in the course of time, said solidified packing becomes somewhat dry it may be readily saturated by filling said inner tubiform barrel with liquid formaldehyde, and that, without altering the scope of my invention, I may substitute packing of cotton, wool, or other suitable material impregnated with any ger- 70 micidal agents.

What I claim and desire to secure by Letters Patent, is,—

The combination with an aseptic clinical thermometer case provided with caps at top 80 and bottom and having an inner flange near its upper end and a metal spring clasp attached within the top cap to receive and support a thermometer of any diameter, of a removable perforated barrel within and 85 spaced from said case and held at the upper end thereof by said flange, the lower end thereof supported by solidified formaldehyde packing in said bottom cap, the space between said barrel and case also constitut- 90 ing a chamber for similar packing.

In testimony whereof I affix my signature in presence of two witnesses.

WASHINGTON I. BROWN.
